INVENTOR

UNITED STATES PATENT OFFICE.

TED E. HISKEY, OF LOS ANGELES, CALIFORNIA.

SAFETY RAZOR.

Application filed March 31, 1928. Serial No. 266,367.

This invention relates to improvements in safety razors of the ribbon steel blade design and has for its object to provide a simple, efficient and inexpensive device of this 5 character.

One of the objects of this invention is to provide a form of safety razor designed to have a diagonal edge for shaving purposes.

Another object of my invention is to provide a safety razor device with few parts, that may be readily cleaned or renewed and capable of guarding against slashes of the face when used rapidly.

A still further object of this invention is 15 to provide means for quickly removing the blade from the razor device to the end that the blade may be readily seated securely in position upon the razor and in this manner serve to deliver a clean cool shave.

Another object of my invention is to provide in a device of the kind set forth means for effecting fine adjustments of the blade in the blade holder part of the safety razor.

Still a further object of this invention is 25 to provide an improved guard for the blade of the razor outfit whereby this guard is located in advance of the blade edge instead of underneath the same.

With the above and other objects in view 30 my invention consists in the combination, arrangement and details of construction disclosed in the drawings and specification and then more particularly pointed out in the appended claims.

In the drawings, wherein similar reference characters designate similar parts throughout the several views,

Figure 1 is a plan view showing the concave surface of the blade cover for the 40 razor,

Figure 2 is a vertical elevation of the blade carrier, partly in section,

Figure 3 is a top plan view of the blade holder,

Figure 4 is a plan view of the razor blade,

Figure 5 is a perspective view of the blade holder,

Figure 6 is a plan view of the razor blade holder,

Figure 7 is a perspective view showing the internal construction of the razor blade holder,

Figure 8 is a side elevation of the razor blade holder,

Figure 9 is another perspective view of 55 the blade holder,

Figure 10 is another elevation view of the blade holder showing the edge of the blade seat,

Figure 11 is a fragmental detail view, 60 partly in section showing the location of the blade carrier upon the holder,

Figure 12 is a vertical elevation of the assembled parts of the completed razor device,

Figure 13 is a side elevation of the razor showing the diagonal cutting edge of the device,

Figure 14 is a rear end elevation of the safety razor device,

Figure 1^a is a perspective view of a modified form of razor,

Figure 2^a is an end elevation of the razor parts,

Figure 3^a is a side elevation of the razor 75 device showing the blade mounted in position thereupon,

Figure 4^a is a bottom plan view of one section of the razor, and

Figure 5^a is a plan view of the other section of the razor.

Referring to the drawings, which are merely illustrative of my invention, a handle 10 threaded as at 11 is formed upon a concavo-convex razor blade carrier which tapers from small as at 12 to large as at 13, whereby the arc distended by the large end is struck on a smaller radius than the small end so that the corner of the part 13 curves around further downwardly than the end designated at 12, providing a diagonal edge 13'. The blade is made of ribbon steel and is narrow, being designated 14, having the sharp cutting edge 15 and the endwise notches 16.

There is provided a tubular razor blade holder 20 having formed thereupon the diagonally disposed slot 21 and having formed upon diametrically opposite points the holes 22, 23 thru which the handle 11 of the blade carrier may project. 19 designates the point where handle 10 is secured to razor blade carrier A.

The blade carrier A is also formed upon its concave side with the endwise notches 17 and 18 designed to receive the pins 24 and 25 disposed at the ends of the blade holder 20 to be more particularly referred to here-

inafter. This blade holder 20 in a plane with the diagonal slot or slit 21 is formed with a diagonal countersunk seat 26 whose shoulder edge appears clearly in Figure 10 5 where it will also be seen that the blade seating and holding pins 24 and 25 project outwardly from the blade holder. Extending in the same direction as the slot 21 is a guard 10 consisting of the comb elements 27 spaced under the blade edge 15 when all the parts are properly assembled.

It will be noted that as the seat 26 is disposed diagonally of the holder 20 and is arcuate in cross section that one end where 15 pin 24 is disposed will extend down farther than the other end where pin 25 is disposed. 30 designates the knurled handle of the device at the upper end of which is the internally threaded stem 28 having the threaded 20 ed bore 28 into which screws the screw 11 of handle 10 of the blade carrier A. The blade 14 is taken and its notched ends 16 seated around the pins 24 and 25 which centers and trues the seating of the blade flat upon the 25 curved arcuate seat 26 of the blade holder 20. Figure 9 shows how this blade seats shows one end of the blade snugly fitting the pin end 25 of the holder 20 while the opposite end of this blade 14 has its edge 30 spaced out of contact with the adjacent curved surface of the holder. Now when all the parts of the razor are assembled in proper order and relation as shown in Figure 12, the handle or post 10 of the carrier A will 35 be introduced into the holes 22, 23; the blade 14 will be seated against the pins 24, 25, the threaded portion 11 of this post will be then entered in threaded relation into the bore 29 of the stem 28 of handle 30; 40 the handle 30 will now be rotated to screw home the threaded portion 11 of the handle 10, thereby causing the lip 13 of the carrier A to extend down so as to engage the end of the razor blade farthest removed 45 from contact with the holder 20, as at 13'; as the rod 11 is screwed home the razor blade is being flexed and curved to the outline of the holder and thereby set the edge and adjust the blade as may be desired for shaving 50 purposes. The tighter the screw handle 30 is screwed home the more securely will the blade be clamped in position. It will now be seen from Figure 13 that the cutting edge 15 of the blade is spaced above the guard 55 comb 27 opposite the slit 21 and the device is then ready for use. Figure 11 shows the ultimate curvature of the razor blade.

I have devised a modification of the razor blade device shown in Figures 1^a, to 5^a inclusive. Here it will become obvious that the handle 18' is secured into one section 13' of the razor device, the other section being designated 14'. The sections are of the same shape being U-shaped on concave in 60 cross section hinged together as by means of

the hinge knuckles 12^a and 27', thru which knuckles the pindle 12' extends to unite movably the two sections.

Section 13' carries the diagonally disposed 70 razor blade 16' in any desired manner and also carries the handle stub 17' by means of which the sections may be opened and closed against the tension of the spring 20' secured at one end by fasteners 21' to section 10' and having a free bearing 19' 75 against the other section, as shown in Figure 2^a.

In this form of my invention one way in which the safety razor blade may be secured is by means of the spring pressed cover 22' 80 hingedly connected as at 25' to one section and having a diagonal bearing upon the section concerned as shown in Figure 3^a. Two rows of pins 20' are carried by the cover plate 22' designed to project into openings 85 19' formed in the blade 16' for the reception of these pins, the section carrying the blade also having corresponding holes formed therein for the pins 20' to project in. A leaf spring 26' is attached to the cover plate 22' and has a coil wound around the pindle 25'; this arrangement allows the cover plate 22' to be lifted with the pins 20' out of engagement with the blade holes 19' against the tension of this spring 26' when it is desired to remove the blade for replacement purposes. When both sections are closed the blade is ready for use. I claim all variations coming within the scope of the appended claims. 95

What I claim and seek to protect by Letters Patent is:—

1. A device as described consisting of a tubular holder having a diagonal slot and a diagonal comb having teeth projecting into said slot, a seat formed upon the tubular holder including a shoulder for the rear edge of the blade, this shoulder also extending diagonally, a narrow razor blade, pins on said holder engaging the ends of said blade for the purpose of retaining it against longitudinal movement from said holder, a cover plate curved in cross section engaging on top of said blade for clamping the same upon said holder in operative position, and means cooperating removably with said cover plate and designed to draw said cover plate clampedly against said razor blade. 110

2. A device as described consisting of a tubular holder having a diagonal slot and a diagonal counterseat to the rear thereof, a flat razor blade arranged diagonally of said tubular holder on said seat so as to extend along said slot, means engaging the ends of said blade and carried by said holder for holding said blade against longitudinal displacement from said holder, a cover plate fitting around the top of said holder and engaging said flat blade to strain said blade 120 125 130 135

resiliently so as to clamp the same in position, and means providing a handle for said holder and extending into said tubular holder for clamping down said cover plate 5 upon said tubular holder.

3. A device as described consisting of a tubular holder having a diagonal slot and a diagonal comb extending longitudinally thereof, a narrow razor blade having terminal notches, pins carried by said holder at opposing ends against which the notched portions of said blade bear, a cover plate engaged upon said blade, and means carried by said holder removably for engaging said 15 cover plate to clamp it against said blade to flex said blade and retain the latter in position.

4. A device of the kind described consisting of a tubular holder having a diagonal 20 slot and a diagonally disposed comb extending in the plane of said slot, said holder being cut away on one side for the purpose of providing a countersunk blade seat also extending diagonally of the slot, the diagonal 25 disposition of said slot and seat causing one end of said seat to curve in a greater arc than the other end, a flat flexible razor blade seated in said diagonal seat so that at one end it fits flush with the bottom of said seat 30 and at another end it is spaced out of contact with the seat bottom, means holding said blade in registration with said slot and manually operated means for clamping said blade upon said holder.

5. A device of the kind described consisting of a tubular holder having a diagonal slot and an adjacent diagonal comb, said holder being formed with a diagonally disposed countersunk seat whereby one end of 40 the seat curves downwardly with respect to the other end, a flat flexible razor blade seated in said holder, fitting said seat, being mounted in contact with the first end of the seat and spaced out of contact with the other 45 curving down end of the seat, a cover plate

arranged to embrace said blade to flex the same making its spaced-from-the seat-end curve into engagement with the seat at this end, and pins on said holder engaging the ends of said blade to make it register with 50 said diagonal slot.

6. In combination a tubular holder having diametrical openings, and having a diagonal slot, a comb confronting said slot and a countersunk diagonal blade seat, pins 55 formed in said holder and disposed at the opposite ends of said countersunk seat, a blade having notches fitting around said pin to give the blade a bearing relatively to said slot and comb, a concavo-convex 60 cover plate engaging said blade for flexing the same to adjust the edge of said blade relatively to said slot by the amount of clamping action imparted to said cover plate, a post projecting from said cover 65 plate thru said openings and ending in a threaded portion, and a handle having a threaded socket into which the threaded end of said post extends to clamp cover plate and blade upon the holder removably but 70 rigidly.

7. A device of the kind described consisting of a tubular holder having a diagonal slot, comb teeth extending from one wall of the slot and partly intersecting said slot, a 75 razor blade seat portion also extending diagonally of said holder with one end curving downwardly with respect to the other end, a flat flexible blade mounted upon said seat portion, and having one end contacting 80 with and its opposite end spaced out of contact with its seat portion, and a cover plate formed concavo-convex longitudinally for clamping said blade upon said holder, said plate being wider at one end than at the 85 other.

In witness whereof he has hereunder set his hand and affixed his seal this seventh day of March, 1928.

TED E. HISKEY. [L. S.]
